UNITED STATES PATENT OFFICE.

THOMAS E. CLARK, OF DETROIT, MICHIGAN.

DESIGN FOR A COMBINED ELECTRIC FAN AND LAMP.

54,832.

Specification for Design.

Patented Apr. 13, 1920.

Application filed October 2, 1919. Serial No. 328,075. Term of patent 14 years.

To all whom it may concern:

Be it known that I, THOMAS E. CLARK, a citizen of the United States, residing at Detroit, in the county of Wayne and State of Michigan, have invented a new, original, and ornamental Design for a Combined Electric Fan and Lamp, of which the following is a specification, reference being had to the accompanying drawing, forming part thereof, in which—

Figure 1 of the drawing is an elevation and Fig. 2 is a plan of a combined electric fan and lamp embodying my new design.

The drawing shows a substantially bell shaped casing for the motor of the fan, the casing have a flaring lower portion which is perforated and within which a fan is rotatable. Wires extend down and then inwardly, meeting at the center to support a lamp bulb centrally of the axis of the bell.

I claim:

The ornamental design for a combined electric fan and lamp, substantially as shown.

THOMAS E. CLARK.
